RETURN ENVELOPE

Willard Woolsey, Chicago, Ill.

Application July 12, 1947, Serial No. 760,671

3 Claims. (Cl. 229—73)

1

This invention relates to mailing envelopes and more particularly to envelopes of the type which may be used to send mail as second class mail and then reused by the recipient to forward a reply, in the same envelope, to be sent as first class mail.

It is one of the objects of the present invention to provide an envelope which may be made on conventional types of envelope making machines from a single sheet of paper which deviates as little as possible from conventional envelope blanks and yet which may be used for two mailings. In accordance with the principles of the present invention a blank sheet is so shaped and constructed that it may readily be made into an envelope for second class mailing and wherein a single dab of adherent serves to secure the envelope together while permitting postal inspection, and wherein the sealing portions of the envelope may be readily torn from the rest of the sheet to permit opening of the envelope and subsequent refolding thereof in a different manner to permit reuse of the envelope, this time for sending first class mail.

It is a further object of the present invention to provide an envelope which is of such a simple construction that the manner of use thereof will be almost self-apparent to the average user thereof so that a simple set of instructions will suffice for the purposes intended.

The attainment of the above and further objects of the present invention will be apparent from the following specification taken in conjunction with the accompanying drawing forming a part thereof.

In the drawing:

Figure 1 is a front view of a blank sheet for forming an envelope of the present invention;

Figure 2 is an end view of the sheet of Figure 1;

Figures 3, 4 and 5 are plan views of the envelope in successive stages of folding;

Figure 6 is a view showing the partially unfolded envelope after a single use thereof; and

Figure 7 is a view of the envelope of the present invention folded for a second use.

Reference may now be had more particularly to the drawing wherein like reference numerals designate like parts throughout.

The mailing envelope of the present invention is formed of a single sheet 1 of paper, of the usual envelope stock, which is cut to provide a central rectangular portion 2, two similar end flaps 3 and 4, and two dissimilar longitudinal side flaps 5 and 6. The end flaps 3 and 4 are adapted to be folded along the lines of fold 7 and 9, re-

2

spectively, to overlie either face of the rectangular portion 2, and likewise the longitudinal side flaps 5 and 6 are adapted to be folded along the lines 8 and 10, respectively, in either direction to overlie either face of the rectangular portion 2. The end flaps 3 and 4 include short tabs 12 and 13, which are adapted to be readily severed from the rest of the sheet, the sheet being provided with weakened lines of severance 14—15 in the form of perforations extending through the sheet. The longitudinal flap 6 is of the general shape of an isosceles triangle and is constructed so that the tip portion 17 may readily be severed from the rest of the sheet, as by the provision of a line of perforations 18. An adhesive coating 19 is applied to the tip portion 17 of the flap 6, said adhesive coating being entirely on one side of the perforations 18. The flap 5 has an adhesive coating 21 along one edge thereof on the side of the sheet opposite the side where the coating 19 is, as may be seen from Figure 2. One side of the rectangular portion 2 may have printed thereon the address of the original sender of the envelope, indicated in the drawing by the arbitrary indication "X. Y. Z Co., Chicago, Ill." The opposite side 2' of the portion 2 receives the address of the first addressee to whom the envelope is to be mailed.

To use the envelope the flaps 3 and 4 are folded over one side of the rectangular portion 2, that is, over the surface thereof seen in Figure 1, thus bringing the structure to the condition illustrated in Figure 3. At this time the edge 23 of the flap 3 is in abutment with the edge 24 of the flap 4, the tabs 12 and 13 being next to one another and the lines of perforation 14—15 being in alignment. Thereafter the flap 6 is folded upwardly to overlie the flaps 3 and 4 so that the tip 17 of the flap 6 overlies the tabs 12 and 13. This is the position illustrated in Figure 4. Immediately prior to the folding of the flap 6 from the position illustrated in Figure 3 to that of Figure 4 the dry adhesive coating 19 is moistened so that upon folding the sheet to the position illustrated in Figure 4 the tip 17 of the flap 6 is adhered to the tabs 12 and 13. At this time the line of perforation 18 overlies the lines of perforations 14 and 15. The structure of Figure 4 is now an open envelope into which mailing material may be placed. After the mailing material has been placed in the envelope the flap 5 is folded along the line of fold 8 and inserted into position between the rectangular portion 2 and the flaps 3 and 4. The envelope is now ready for mailing as second class mate-

rial, since it is an unsealed envelope. At this time the tip 17 overlies and is adhered to the tabs 12 and 13 which in turn overlie the flap 5. This is the condition of the envelope as seen in Figure 5.

The side of the rectangular portion 2 opposite to that illustrated in Figure 1 is addressed to the party to whom the envelope is to be mailed. When that party receives the letter he need merely tear off the tip 17 and with it the adhered tabs 12 and 13, the tearing being along the perforated lines of tear 18 and 14 and 15. When that is done the envelope may be unfolded. Thereafter, if the envelope is to be reused the flaps 3 and 4 are then folded over the opposite face of the rectangular portion 2, that is, over the face 2'. The flap 6 is then again folded along the line 10, but in the direction opposite to the previous fold, so that the flap 6 again overlies the flaps 4 and 3. The flap 5 is then folded over the flap 6 and on the outside of the flaps 3 and 4, and the dry adhesive 21 is moistened to adhere the flap 5 to the flaps 3, 4 and 6, thus providing a sealed envelope of Figure 7 for first class mailing.

While I have shown an arrangement wherein the coating 19 for adhering the flap 6 to the tabs 12 and 13 is initially applied to the tip portion 17, it may instead be applied to the corresponding sides of the flaps 12-13, in which case the adhesive would be on the same side of the sheet 1 as is the adhesive 21 on the flap 5.

From the above description it is apparent that I have provided a mailing envelope which can be sent out with mailable matter therein and in a closed but unsealed condition, so that the envelope is mailed as second class mail from the original sender to a prospective customer. After the customer has opened the envelope he can refold the sheet in a very simple manner to form another envelope in which he can place his order and which can then be sealed and mailed back to the original sender as sealed, first class mail. All of this may be done in a simple and expedient manner. It is further apparent that the envelope of the present invention involves a minimum departure from standard envelope manufacture and requires a minimum surplus of paper.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. Means for forming a mailing envelope comprising a single sheet including a rectangular portion having transverse end flaps and first and second longitudinal side flaps extending from the respective transverse ends and longitudinal sides of the rectangular portion, the respective flaps being foldable to alternate positions overlying the opposite faces of the rectangular portion, the transverse flaps having integrally formed tabs adjacent one another and adjacent the longitudinal edge of the first longitudinal side flap when the transverse flaps are in folded position, the second longitudinal side flap having a part which in the flap folded position overlies the tabs, weakened lines of severance between said part and the

rest of the sheet and also between said tabs and the rest of the sheet, said weakened lines of severance being superposed when the flaps are in their folded positions.

- 5 2. Means for forming a mailing envelope comprising a single sheet including a rectangular portion having transverse end flaps and first and second longitudinal side flaps extending from the respective transverse ends and longitudinal sides 10 of the rectangular portion, the respective flaps being foldable to alternate positions overlying the opposite faces of the rectangular portion, the transverse flaps having integrally formed tabs adjacent one another and adjacent the longitudinal edge of the first longitudinal side flap when the transverse flaps are in folded position, the second longitudinal side flap having a part which in the flap folded position overlies the tabs, weakened lines of severance between said 15 part and the rest of the sheet and also between said tabs and the rest of the sheet, said weakened lines of severance being superposed when the flaps are in their folded positions, and adhesive on said sheet for adhering said part and both 20 said tabs together while leaving the rest of the superposed parts of the folded sheet separate so that upon tearing of the envelope at said weakened lines of severance the flaps may all be folded over the opposite face of the rectangular portion.
- 25 3. Means for forming a mailing envelope comprising a single sheet including a rectangular portion having transverse end flaps and first and second longitudinal side flaps extending from the respective transverse ends and longitudinal sides 30 of the rectangular portion, the respective flaps being foldable to alternate positions overlying the opposite faces of the rectangular portion, the transverse flaps having integrally formed tabs adjacent one another and adjacent the longitudinal edge of the first longitudinal side flap when the transverse flaps are in folded position, the second longitudinal side flap having a part which in the flap folded position overlies the tabs, weakened lines of severance between said 35 part and the rest of the sheet and also between said tabs and the rest of the sheet, said weakened lines of severance being superposed when the flaps are in their folded positions, an adhesive on said sheet for adhering said part and both said tabs together while leaving the rest of the superposed parts of the folded sheet separate so that upon tearing of the envelope at said weakened lines of severance the flaps may all be folded over the opposite face of the rectangular portion, 40 and an adhesive coating along an edge of the first longitudinal flap that then overlaps the second longitudinal flap.

WILLARD WOOLSEY.
